J. F. GRAHAM

TIRE CHAIN FASTENER

Filed March 3, 1924.

P. J. Hickey
Thos. E. Turpin

WITNESS

J. F. Graham,
INVENTOR
BY *Victor J. Evans*
ATTORNEY

UNITED STATES PATENT OFFICE.

JOSEPH F. GRAHAM, OF TUNNELTON, WEST VIRGINIA.

TIRE-CHAIN FASTENER.

Application filed March 3, 1924. Serial No. 696,679.

To all whom it may concern:

Be it known that I, JOSEPH F. GRAHAM, a citizen of the United States, residing at Tunnelton, in the county of Preston and 5 State of West Virginia, have invented new and useful Improvements in Tire-Chain Fasteners, of which the following is a specification.

The object of my said invention is the 10 provision of a tire chain fastener susceptible of quick and easy operation and adapted to safely and strongly hold a tire chain under tension on an automobile or other vehicle wheel.

15 To the attainment of the foregoing, the invention consists in the improvement as hereinafter described and definitely claimed.

In the accompanying drawings, forming part of this specification:—

20 Figure 1 is a plan view of my novel fastener in open state.

Figure 2 is a similar view showing the fastener as closed and secured in closed state.

25 Figure 3 is an edge elevation of the closed fastener.

Figures 4 and 5 are detail views herein-after explicitly referred to.

Similar numerals of reference designate 30 corresponding parts in all of the views of the drawings.

My novel fastener is formed of appropriate wire and includes among other elements a U-shaped body 1 with eyes 2 at 35 its ends. The fastener also comprises a tongue 3 and a keeper 4, the said keeper being adapted to be detachably secured in closed position relative to the body 1 and to securely fasten the tongue 3 in working 40 position.

As clearly illustrated the tongue 3 is provided with a loop 4^x at its heel, and the said loop terminates in lateral journals 5 disposed in the eyes 2 and retained by hooks 45 6 in said eyes.

As will be understood by comparison of Figures 1, 2 and 3, the loop 4^x extends at right angles to and at one side of the plane of the journals 5, while the major portion 50 of the tongue 3 extends at the opposite side of the journals 5 and lies in the same plane as both sides of the loop 4^x. Manifestly when formed as illustrated the tongue and its appurtenances are comprised in a single 55 stiff and strong element.

The keeper 4 includes a bail portion 7 adapted to straddle the closed tongue 3, Figures 2 and 3, and also includes coils 8 mounted on the bight of the body 1 and arms 9. Both the bail portion 7 and the 60 arms 9 are resilient, and the arms 9 terminate in outwardly directed hooks 10 which are adapted to be sprung into and out of engagement with the side portions of the body 1. Manifestly when the hooks 65 10 are so engaged with the side portions of the body 1, the tongue 3 will be securely retained in the closed position shown in Figures 2 and 3 while when the said hooks 10 are disengaged from the body 1 and 70 the keeper 4 is swung to open position the tongue 3 can also be swung to open position.

The tongue 3 in use is adapted to receive the end of a tire chain which is permanently connected to the opposite end of the fastener, and when the tongue 3 is swung to closed position it will take up slack in the chain, and then when the keeper 4 is secured over the closed tongue, the chain will be 80 strongly held under tension and in working position.

Notwithstanding the practical advantages of my novel fastener, it will be noted that the fastener is simple and inexpensive in 85 construction and is well adapted to withstand the rough usage to which wheel appurtenances are ordinarily subjected.

I have entered into a detailed description of the construction and relative arrangement of parts embraced in the present and preferred embodiment of my invention in order to impart a full, clear and exact understanding of the said embodiment. I do not desire, however, to be understood as 95 confining myself to the specific construction and relative arrangement of parts inasmuch as in the future practice of the invention various changes and modifications may be made such as fall within the scope 100 of my invention as defined in my appended claim.

Having described my invention, what I claim and desire to secure by Letters-Patent, is:—

A tire chain fastener comprising a U-shaped body having eyes at its ends, a tongue having a loop at its heel and also having lateral journals disposed in said eyes and terminating in hooks, the said 110

tongue loop extending at right angles therefrom, and the major portion of the tongue resting in the same plane as the loop and extending at the opposite side of the plane of the journals, and a keeper having coils surrounding the bight of the body and also having a loop arranged to a straddle the

tongue and resilient arms terminating in outwardly directed hooks adapted to be sprung into and out of engagement with the side portions of the body.

In testimony whereof I affix my signature.

JOSEPH F. GRAHAM.
